MAX SCHMIDT AND EMIL NEUBACHER, OF CINCINNATI OHIO, ASSIGNEES TO THE
MAX WOCHER & SON COMPANY, OF CINCINNATI, OHIO, A CORPORATION OF OHIO.

BEDSIDE UTILITY TABLE.

Application filed November 21, 1925. Serial No. 70,557.

Our invention relates to the construction of beside tables and particularly to the kind having an adjustable and collapsible utility leaf combined therewith.

5 The objects of our invention are to provide simple, efficient, compact and conveniently and easily operated means for elevating and lowering and of folding either to open or closed position an auxiliary or utility leaf; 10 to provide such a construction which is positive in its action and so made that persons adjusting the leaf are not likely to pinch their fingers when raising or lowering the leaf.

Another object of the invention is to so 15 construct and arrange the parts as to eliminate to a minimum the amount of noise when raising or lowering the utility leaf.

Our invention consists in providing a bedside table (which may have a plurality of 20 compartments therein) with an auxiliary manually operative utility leaf supported by said bedside table and in providing simple, efficient and durable mechanism for supporting and collapsing the utility leaf when in elevated position for use or in collapsed position when not in use.

Our invention also consists in the construction, combination, location and arrangement of parts, as herein set forth and claimed.

30 In the drawings:

Fig. 1 is an isometric view of a construction showing an embodiment of our invention with the leaf in open or supporting position;

35 Fig. 2 is a front elevation of the invention showing the utility leaf in position for use, and showing by dotted lines, its position in extreme elevated position and also in position when collapsed;

40 Fig. 3 is an isometric view, enlarged, of one of the guide supports;

Fig. 4 is a side elevation showing the releasable clamp and other parts mounted on the standard with parts in dotted lines and parts broken away;

45 Fig. 5 is an isometric view of the leaf supporting structure shown apart from the bedside table and showing parts broken and in dotted lines;

Fig. 6 is a longitudinal section of the leaf 50 supporting arm and parts related thereto

shown on a plane corresponding to line 6—6 of Fig. 5;

Fig. 7 is a bottom view of the leaf;

Fig. 8 is a side elevation of the lower portion of the standard showing a shock absorbing spring therein; 55

Fig. 9 is a modified construction, partly in elevation and partly in section, showing the leaf in open or horizontal position, the table being indicated by dotted lines; 60

Fig. 10 is a view, partly in section, showing the leaf in closed or lowered position, the table being partly broken away;

Fig. 11 is an isometric view, enlarged, of the rubber buffer; 65

Fig. 12 is an isometric view showing the lower side of said buffer;

Fig. 13 is a cross-section on the line 13—13 of Fig. 9.

In the embodiment of our invention, as illustrated, and which shows a preferred construction, we provide a bedside table of the usual well known construction, comprising casing 2 having sides 3, 4, 5, and 6, respectively, and top 7. The casing 2 is supported by 70 legs 8, which are provided with castors 9 for convenience in moving the table from place to place. Casing 2 also contains a plurality of compartments, such as drawer 10 and storage place therebelow, closed by door 11. 75

Supporting brackets 12 and 13 are spot-welded or otherwise secured to side 5 of casing 2 and have guide supports 14 and 15, respectively, fixed thereto by screws 16 which are received by holes 17 in said guide supports. 80

Standard 19 is slidably mounted in hole 20 in guide support 14 and in hole 21 in guide support 15. The lower portion 22 of standard 19, received by hole 21 in guide support 90 15 is provided with slots 23 in its opposite walls for the purpose of clearing pin 24 horizontally fixed in holes 25 in guide support 15. Coil spring 26, whose outer periphery is slightly smaller than the inner walls 27 of 95 hollow standard 19, is mounted in said standard with its lower end resting on pin 24. Standard 19 is also provided with pin 29, which extends horizontally from front 30 to back 31 thereof. 100

Disc-shaped ear 33 is provided with reduced shank 32, which is adapted to snugly fit in the upper end of standard 19 to which it is fixed. Said disc-shaped ear 33 is inserted in channel 34^a between the bifurcations of end 34 of supporting arm 35 and has frictional pivoted relation therewith, as by bolt 36 and nut 37. The upper end of standard 19 is provided with handle 38, preferably U-shaped, having its lower ends 39 secured to standard 19 and shank 32 by screws 40.

Channel 34^a extends longitudinally on the lower side of supporting arm 35 and receives disc-shaped ear 33, latch 41, coil spring 42 and spring retaining member 43. Latch 41 is slidably held within channel 34^a by plate 44 fixed to the underside of supporting arm 35 by screws 45 and its end 42^a is provided with coil spring retaining pin 41^b and manually 20 operated pull handle 41^c projecting laterally therefrom. The other end 41^a of latch 41, engages notch 33^a of disc-shaped ear 33 to support the utility leaf in open horizontal position. Supporting arm 35 is provided with 25 lugs 35^a and 35^b, respectively, for the purpose of supporting frame 46 on the underside 47 of utility leaf 48.

Guide support 14 is provided with integral bracket 14' thereon and guide support 15 is provided with integral bracket 15' thereon.

As shown in Fig. 4, supporting rod 57 is fixed to and suspended from bracket 14' in fixed relation with bracket 15', and extends through hole 51^a in releasable clamp 51. Releasable clamp 51 is provided with slot 51^b for the purpose of receiving standard 19 to which said releasable clamp is pivoted at 52. Clamp releasing rod 53 has its lower end 53^a reduced or attenuated to form shoulder 53^b and passes through hole 51^c near the end of releasable clamp 51. The upper end 53^c of clamp releasing rod 53 passes upwardly through one side of U-shaped handle 38 and has hand hold 53^d spaced apart and parallel to top 38^a of U-shaped handle 38 and downwardly bent portion 53^e through top 38^a of U-shaped handle 38, as clearly shown in Figs. 1 and 5. Angular bracket 54 (Fig. 4) is spaced above end 51^d of releasable clamp 51 and fixed to the side of standard 19 by screws 55. Coil spring 56 is inserted between angular bracket 54 and end 51^d of releasable clamp 51 and retained therebetween by pin 54^a. The purpose of coil spring 56 is to maintain pressure on end 51^d of releasable clamp 51, thereby causing end 51^e of said clamp to bear upwardly on its pivot 52 whereby the weight of standard 19, leaf 48 and their connected parts cause the wall of hole 51^c to bind on supporting rod 57 thereby preventing vertical movement of said standard except when said clamp is released from said holding rod.

A rubber buffer 58 is mounted near the

upper end of standard 19 for the purpose of 65 engaging supporting arm 35 when utility leaf 48 is dropped to collapsed position, as shown by dotted lines in Fig. 2, and thereby preventing noise.

To operate the device, we will assume that 70 utility leaf 48 is in position for use, as shown in Figs. 1 and 2. When it is desired to collapse or drop utility leaf 48 simply draw outwardly on manually operated pull handle 41^c thereby comprising coil spring 42 and drawing end 41^b of latch 41 out of engagement with notch 33^a in disc-shaped ear 33. This allows supporting arm 35 to pivot on bolt 36 and to swing down to the position shown by dotted lines in Fig. 2. Should it be desired to put 80 the utility leaf into use when it is in the folded or collapsed position, simply raise the leaf until coil spring 42 automatically forces end 41^d of latch 41 into supporting relation with notch 33^a of disc-shaped ear 33. 85

To elevate the utility leaf, we will assume that it is in the position shown by full lines in Figs. 1 and 2. Place the hand beneath top 38^a of U-shaped handle 38 and simultaneously manually grip hand hold 53^d of clamp releasing rod 53, thereby depressing said clamp releasing rod 53 against releasable clamp 51 which brings said clamp to horizontal position and disengages the binding on the wall of its hole 51^c of supporting rod 57. This 90 allows the standard and leaf to be raised to any desired height where they are retained by merely releasing the hand from U-shaped handle 38 and hand hold 53^d thereby releasing the downward pressure on clamp releasing rod 53, whereupon coil spring 56 causes end 51^e of releasable clamp 51 to bear downwardly, and said clamp, being pivoted at 52, causes end 51^e to bear upwardly into binding and holding relation with supporting rod 57. 100 The position of releasable clamp 51, just described, as shown in Fig. 4, causes hole 51^c to be tilted at an angle relative to supporting rod 57 so that the weight of leaf 48, standard 19 and connected parts, tend to bear down 110 thereby causing binding of the wall of hole 51^c upon supporting rod 57 whereby the utility leaf is held at any desired adjusted height. 105

Coil spring 26 seated on pin 24 within 115 hollow standard 19 is for the purpose of providing a buffer to take up the shock and jar and prevent noise by contact of the parts and particularly so, should the person lowering the leaf, fail to release the hand pressure on hand hold 53^d of clamp releasing rod 53, thereby avoiding any noise or jar of leaf 48 when hollow standard 19 reaches its extreme downward position. This extreme downward position is determined by transverse pin 120 29 resting on the upper end of coil spring 26 and prevents shoulder 33^b from striking the top of upper guide support 14. 125

While we have set forth a preferred construction it will be understood that various modifications may be made without departing from the scope or spirit of the invention, 5 as defined in the claims, as for instance, in Figs. 9, 10, 11 and 12 we have illustrated modifications which will now be described:

In the modified construction the disc-shaped ear 59 is provided with base 59' having reduced shank 60 of rectangular shape adapted to fit within standard 19' and is secured thereto by means of taper pin 61 driven transversely through said standard and shank. Rubber buffer 62 (Figs. 11 and 12) is 10 interposed between base 59' and guide support 14 to form a cushion therebetween when said base is lowered from elevated position to a position resting upon said cushion. Said buffer is preferably provided with integral rubber projections or points 62' adapted to 15 take up the initial pressure or impact on the cushion. Said cushion is also provided with front projection 62'' which serves as a buffer when utility leaf 48 is lowered from horizontal 20 or operative position to vertical or inoperative position, thereby preventing noise and jarring of the parts. In this construction, also, handle bar 63 is attached to latch 41 and extends outwardly to near the free end 25 of utility leaf 48, it being mounted to slide in guide 64. It is also provided with a handle 65 which is located near the end of leaf 48 so that when it is desired to lower utility leaf 48 the handle may be readily grasped and drawn 30 outwardly by one hand thereby releasing latch 41 and permitting the leaf to be swung from the position shown in Fig. 9 to that shown in Fig. 10. When it is desired to raise the table from inoperative position, shown 35 in Fig. 10, to operative position, shown in Fig. 9, simply take hold of leaf 48 and raise it to its open or horizontal position, whereupon the latch will automatically engage the holding notch and retain the leaf in horizontal 40 position.

In this construction, also, we have shown legs 8' of table 1 extended beyond standard 19' in order to insure the table from tipping or upsetting if the leaf should have a heavier 45 weight than the combined weight of table 1 and its contents.

An important advantage of this invention consists in the convenient means whereby the utility leaf may be readily adjusted by one 50 hand of the operator to any desired height and whereby the utility leaf may be drawn from inoperative to operative position by one hand of the operator and automatically latched in operative position.

Another very desirable feature of the invention consists in the rubber buffer which performs the triple functions of compensating for the initial and final impact of the jar caused by the sudden contact of the collid-

ing parts when the standard is moved to its 65 lowermost position and also when the leaf is swung downwardly upon its pivot into contact with said buffer.

What we claim as new and desire to secure by Letters Patent is:

1. An attachment for a table comprising a pair of spaced apart supporting brackets secured to said table, guide supports fixed to said supporting brackets, a standard slidably received by said guide supports and having a manually operative handle fixed to the upper end of said standard, a bracket on each guide support, a holding rod held in vertical stationary position by said brackets, a releasable clamp pivoted to said standard and engaging said holding rod, a disc-shaped ear fixed to the top of said standard and having a notch therein, a supporting arm pivotally attached to said ear, a leaf on said arm, and a latch on said arm engaging said notch. 80

2. An attachment for a table comprising supporting means, guide supports fixed to said supporting means and having vertical openings therethrough, a standard, a supporting arm pivotally connected to said standard, a leaf supported by said supporting arm, a disc-shaped ear fixed to the upper end of said standard, and having a notch therein, a latch slidably received by said supporting arm and engaging said notch for the purpose 95 of supporting said supporting arm in elevated position, a handle for said standard, a clamp pivotally mounted on said standard, a bracket fixed to each guide-support, a binding rod held by said brackets and extending through said clamp, a clamp releasing rod mounted in said handle and extending through the upper of said brackets and through said clamp and having a shoulder near its end to engage said clamp, and means to operate said clamp releasing rod. 100

3. An attachment for a table comprising a supporting structure, a standard slidably mounted on said structure, a leaf pivotally connected to said standard, a clamp on said standard, a handle fixed to the upper end of said standard, and a clamp releasing rod mounted in said handle and engaging said clamp. 110

4. An attachment for a table comprising a supporting structure, a standard slidably mounted on said structure, a leaf pivotally connected to said standard, a clamp on said standard, a handle fixed to said standard, a clamp releasing rod mounted in said handle and engaging said clamp, a pin in said standard, a spring received in the lower end of said standard and engaging said pin when said standard is in its extreme lower position. 120

5. An attachment for a table comprising a supporting structure, a vertically adjustable standard slidably mounted thereon and having a handle on its upper end, pivoted means

adapted to hold said standard in any adjusted position, releasing means connected to said pivoted means and having operative means adjacent said handle whereby said pivoted means is adapted to be released.

6. An attachment for a table comprising a supporting structure, spaced apart hollow guide supports, a standard slidably mounted in said guide supports and having an ear on its upper end provided with a curved periphery having a notch therein, a shoulder on said standard, a rubber buffer embracing said standard and interposed between said shoulder and the upper guide support and having 10 projections thereon adapted to compensate for the initial shock when said standard and connected parts are brought to their lowermost position, an arm pivoted to said ear, a leaf carried by said arm, a latch, a spring 15 carried by said arm and adapted to move said latch into operative engagement with said notch and a handle attached to said latch whereby it is adapted to be withdrawn from operative engagement with said notch to permit 20 said leaf to be swung upon its pivot.

7. An attachment for a table comprising supporting means, spaced apart guide supports on said supporting means, a bracket on each guide support, a holding rod connected 30 to and held by said brackets, a standard slidably mounted in and supported by said guide supports, a clamp pivotally attached to said standard, a spring adapted to hold said clamp in adjusted holding engagement with said holding rod, and a clamp releasing rod adapted 35 to move said clamp into and out of holding engagement with said holding rod.

8. An attachment for a table comprising spaced apart guide supports attached to said table, a vertical standard slidably mounted in said guide supports, a stationary holding rod connected to said guide supports, a slotted clamp embracing said standard and pivoted thereto, said clamp having a hole there-through embracing said holding rod, a spring mounted on said standard and bearing against one end of said clamp, a handle on the upper end of said standard, a clamp releasing rod having its lower end in engagement with said clamp and having a hand hold adjacent said handle, whereby said clamp is adapted to be moved out of holding engagement with said stationary rod to permit said standard to be vertically adjusted by the hand of the operator, and a leaf pivotally mounted on said standard and adapted to be held in either horizontal or vertical position.

9. An attachment for a table comprising spaced apart hollow guide supports each having a bracket with holes therethrough, a standard vertically mounted in said guide supports, a leaf supported by said standard, a holding rod mounted in the holes of said brackets and screwed to the upper bracket, a

slotted clamp pivoted to said standard between said supporting guides, a spring carried by said standard and mounted in engagement with one end of said clamp, a handle on said standard and having holes therein, a clamp releasing rod extending through said holes in said handle and normally spaced apart from the upper end thereof to form a hand-hold, said clamp releasing rod extending through said upper bracket and having a reduced end extending through said clamp 70 with a shoulder thereon adapted to bear against said clamp when said clamp releasing rod is moved downwardly by the operator when grasping said hand-hold and handle whereby said clamp is forced downwardly 75 out of holding engagement with said holding rod and whereby, when the hand is released, said clamp will engage said holding rod at any desired point thereon to support said leaf 80 at any desired height.

10. An attachment for a table comprising supporting means, spaced apart guide supports attached to said supporting means, a standard mounted in said guide supports and having a shoulder near its upper end, a handle on said upper end, a leaf pivoted to said upper end and means for holding said table either in horizontal or vertical position, a rubber buffer having a hole therethrough fitting upon said standard beneath said shoulder and projecting outwardly beyond said shoulder to engage said leaf when it is dropped to vertical position and means for adjusting said standard vertically whereby when it reaches its lowermost position said 90 rubber buffer will contact with the upper 95 guide support and whereby the noise of making such adjustment is reduced to a minimum.

11. An attachment for a table comprising spaced apart guide supports attached to one side of said table, a vertical standard mounted in said guide supports and having a shoulder near its upper end in combination with a hollow rubber buffer embracing said standard adjacent said shoulder and having an extension on its side away from said table projecting beyond said shoulder, and projections on its lower side adapted to engage the upper of said guide supports, and a pivotally mounted leaf adapted to engage said extension when said leaf is dropped to its vertical position whereby the noise is deadened.

12. In utility tables, spaced apart guide supports each having a bracket thereon, a standard in said guide supports, a pivotally mounted leaf on said standard, a releasable clamp pivotally mounted on said standard and having holes therethrough near one end, a holding rod fixed to said brackets and extending through said releasable clamp, a handle on said standard, a clamp releasing rod

mounted in said handle and extending through the upper of said brackets and through said releasable clamp and having a shoulder near its end to engage said releasable clamp.

13. An attachment for a table comprising a supporting structure, a standard mounted for vertical movement therein and provided with a handle, a leaf pivotally connected to

the upper end of said standard, locking means adapted to hold said standard in any desired adjusted position relative to the supporting structure, and means adjacent said handle for releasing said locking means, whereby said last-mentioned means and handle can be 15 operated simultaneously by one hand.

MAX SCHMIDT.
EMIL NEUBACHER.
